BOTTLE CAP

David L. Lundberg, 3417 S. 77th St.,
Omaha, Nebr. 68124

Filed Mar. 24, 1969, Ser. No. 16,413

Term of patent 14 years

Int. Cl. D9—02

U.S. Cl. D9—275

FIG. 1

FIG. 7

FIG. 2

FIG. 3

FIG. 4

FIG. 5

FIG. 6

FIG. 1 is a perspective view of the bottle cap showing my new design;

FIG. 2 is a front elevational view thereof with the closure thereof in an open position;

FIG. 3 is a side elevational view thereof with the opposite side being a mirror image thereof;

FIG. 4 is a rear elevational view thereof;

FIG. 5 is a bottom plan view thereof;

FIG. 6 is a top plan view thereof; and

FIG. 7 is a perspective view of the bottle cap mounted on a bottle, the bottle being shown in broken lines for illustrative purposes only.

I claim:

The ornamental design for a bottle cap, substantially as shown and described.
